H. B. SMITH.
AUTOMATIC SCREEN GATE.
APPLICATION FILED APR. 25, 1917.

1,256,837.

Patented Feb. 19, 1918.

UNITED STATES PATENT OFFICE.

HARRY B. SMITH, OF MERRITT, WASHINGTON.

AUTOMATIC SCREEN-GATE.

1,256,837.

Specification of Letters Patent. Patented Feb. 19, 1918.

Application filed April 25, 1917. Serial No. 164,371.

To all whom it may concern:

Be it known that I, HARRY B. SMITH, a citizen of the United States, residing at Merritt, in the county of Chelan and State 5 of Washington, have invented certain new and useful Improvements in Automatic Screen-Gates, of which the following is a specification.

This invention relates to automatic screen 10 gates and has for its principal object to provide an improved and novel type of automatic screen gate for use in flumes, dams, etc., where it is necessary to close the flume against the passage of fish and at the same 15 time provide means for allowing the passage of drift wood and other foreign matter which might obstruct the flume or the stream. A further object of my device is to provide shuttle screens which present alternate faces to the direction of flow of 20 water in the flume, thereby making them self cleaning.

In irrigation systems and the like, fish 25 have a tendency to travel up the flumes and ditches similarly to traveling up creeks and rivers and as the water is frequently directed from the flumes and ditches, it is found that many fish are killed and lost. A law has recently been passed in this State 30 and it is believed also in other States, which requires that gates be installed in the entrance to flumes and ditches in order that the fish may be prevented from entering the said flumes and ditches. My device is 35 designed to meet the requirements of the law and at the same time prevent the accumulation of debris which would seriously obstruct the gates.

Other objects will appear as my invention 40 is more fully explained in the following specification, illustrated in the accompanying drawings and pointed out in the appended claims:

In the drawings, Figure 1 is a front elevation of my device shown in a flume with 45 parts broken away along line $x-x$ of Fig. 2. Fig. 2 is a side elevation of my device with part of the flume broken away. Fig. 3 is an enlarged fragmentary section of a 50 shuttle screen.

Referring more particularly to the drawings, numeral 1 indicates the bottom of a flume which is provided with sides 2, all of which is properly held together by means 55 of a frame 3. In the location of the gate, side frames 3 are continued up well above

the top of the flume and are provided with a cross beam 4. My automatic gate is positioned beneath cross beam 4 and is set in bearings 5 which are supported on the top 60 of the flume. My device consists of a wheel composed of four similar arms 6 of equal length on either end of the wheel. The four armed wheel ends are positioned parallel to each other and adjacent the sides of the 65 flume. They are tied together at their outer ends by means of struts 7 and are supported in bearings by stub shafts 8 which are integral with flanges 9. The flanges are bolted or otherwise fastened centrally of the wheel. 70 Each arm of the wheel is preferably formed of angle arms spaced apart with a continuous channel 10 between them. The arms 6 are so arranged that the channels 10 are continuous from end to end of oppositely 75 positioned arms. A pair of shuttle screen frames 11 are mounted within channels 10. Screen frames 11 are provided with rollers 12 which roll along the arms 6, thereby preventing undue friction between the screen 80 frames and the arms. Screen frames 11 are covered with a wire mesh 13 which prevents fish from passing up the flume and at the same time permits the flow of water down the flume. The device as shown in the 85 drawings, is set in operative position in the flume and it is normally maintained in said position by means of a spring catch 14 which is secured to head beam 4. The foot spring 15 may also be set in the bottom of 90 the flume if necessary to assist in retaining the gate in normal position. When debris drifts down the flume and lodges against the screen in sufficient quantity to obstruct 95 the flow of water, the pressure will become 100 sufficient to dislodge the wheel from the retaining springs and permit it to revolve. As soon as the wheel starts to revolve, the screen which is in a horizontal position and is not operating, will roll along the channel 10 in a normal position to the flume, whereas the screen which has just moved out of position will assume a horizontal position above the water surface of the flume and all the loose debris will drop from the screen and 105 pass on down the flume. The next successive and similar operation will bring this screen again into normal position with its opposite side up the stream, thereby permitting the flow of water to completely 110 clean the screen. The second operation is in each way similar to the first, except that

the screens interchange their functions. Springs 14 and 15 are designed to catch and hold the wheel from any rotation in excess of 90 degrees and to release the wheel only when considerable pressure is brought to bear on the screen and the flume. It will be seen that my gate is automatic, self cleaning and requires no attention other than an occasional inspection. The shuttle screens which present alternate faces to the direction of the flow of water is a very important feature of my device and obviates the use of more than two screens as well as making the screens self cleaning. Brace rods 16 may be used to stiffen the frame generally.

While I have shown a particular form of embodiment of my invention, I am aware that many minor changes therein will readily suggest themselves to others skilled in the art without departing from the spirit and scope of the invention, and I therefore desire to avoid being limited to the exact form shown and described.

Having described my invention, what I claim as new and desire to protect by Letters Patent, is—

1. In a device of the class described, the combination of a wheel having armed ends which are spaced apart, parallel diametrical channels in the said wheel ends, shuttle screens movably mounted in said channels, and means for retarding the said wheel against rotary movement.

2. In an automatic screen gate for streams, the combination of a diametrically chan-

neled wheel revolvably mounted in said stream, shuttle screens slidably mounted in said channels, means for normally retaining said wheel against rotation, whereby when the wheel is in such position that one of the screens is submerged in an approximately vertical position in the stream, it will be so retained until sufficient debris has collected against the up stream face of the said screen to cause the release of the wheel from the retaining means and allow the wheel to revolve until another shuttle screen comes into normal position.

3. In an automatic revolving screen gate for streams, the combination of a pair of shuttle screens arranged normally in horizontal and vertical planes, whereby the vertical screen is positioned transversely the stream and the horizontal screen is above the water surface, revolving wheel means for supporting said screens in normal position, channels in the said wheel within which the said shuttle screens are slidably mounted, means for normally retaining the said wheel against rotation and for releasing the said wheel for a predetermined amount of rotation, whereby when a sufficient amount of debris is collected against the face of the vertical screen, it will cause the wheel to revolve, thereby removing the vertical screen from out of the stream and allowing the horizontal screen to slide into a vertical position in the stream.

In testimony whereof I affix my signature.
HARRY B. SMITH.
